UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed May 4, 1922. Serial No. 558,357.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

The present invention relates to work- 10 sheet feeding and controlling mechanism for typewriting machines. More particularly the invention relates to typewriting machines in which two sheets set side by side upon a single unitary platen may be writ- 15 ten upon alternately and have line-feed movement independently of each other. The sheets at one side may, for instance, be individual bills or forms, and those at the other side be ledger accounts or classified total- 20 ling sheets; and, in a machine of the character mentioned, the entries may be made on the ledger or totalling sheet, as the work on the individual sheets progresses, without necessitating repeated withdrawals and in- 25 sertions of the ledger or totalling sheet.

An object of the present invention is the provision of means, independent and free of the platen, for effecting line-space movement, over the platen, of the sheet (preferably the ledger or totalling sheet), at one side of the platen; thus, as to such sheets, eliminating the pressure rolls which ordinarily hold the sheets to the platen and cause the same to be moved therewith.

35 The platen being cleared of all feeding devices, say for the ledger sheet, there is no feeding mechanism to be released from the platen and no holding means to be applied to the ledger sheet every time the 40 platen is to be moved with the other or individual form sheet; and likewise it becomes unnecessary to release the individual form sheet and to secure the same against movement every time the other sheet is to be moved. By means of the present invention, therefore, the operation of writing on the two sheets, as well as the mechanism involved, is much simplified. Of course it will ordinarily not be necessary to remove 45 from the machine any of the feed rolls usually present: certain of these may be fixed in released position for the character of work above mentioned, and may be used for other work.

55 A feature of the invention is the provision

of a sheet-feeding device, for the purpose mentioned, independent and free of the platen, which shall also serve as a means for holding a sheet in proper printing position while the platen moves with a sheet at the 60 other side thereof.

In the preferred form of the invention, the means for receiving and holding one set of sheets independently of the platen comprises a set of opposed rolls between which 65 the sheet is gripped, and means such as a thumb wheel for turning these rolls; these rolls being supported on the carriage above the platen, preferably at a point about midway of the platen, and being releasable one 70 from the other for easy insertion of the sheets.

A further object of the invention is the provision of a shelf against which erasures may be made on the sheet which is fed independently of the platen. Ordinarily, 75 to effect an erasure, the platen is slightly turned to bring the printing to be altered to a position where it is clear of the printing instrumentalities, and the erasure is then made against the platen. Where, as in the 80 present invention, one of the sheets may not move with the platen, it may nevertheless be moved by its own feeding device to bring, to the shelf just mentioned, the printing which is to be erased. A feature of the 85 invention is the provision of means, preferably the shelf referred to, or an extension thereof, for guiding the sheets to the feeding device, and for preventing fouling of the sheets on the supports and the operating mechanism of such feeding device.

90 Other features and advantages will hereinafter appear.

In the accompanying drawings, Figure 1 is a front elevation of a platen-frame of an Underwood front-strike typewriting machine, showing the invention applied thereto.

Figure 2 is a view in cross-sectional side elevation on the line 2-2 of Figure 1; the feed-rollers for the right-hand sheet being shown in effective position.

Figure 3 is a view similar to Figure 2, except that the feed-rollers for the right-hand sheet are shown in released position, 105 and certain parts shown in Figure 2 are omitted.

Figure 4 is a view in side elevation, looking toward the right-hand end of the platen-frame.

Figure 5 is a view, in side elevation, of the plate which supports the left-hand end of the feeding mechanism for the right-hand sheet; this plate being shown in its 5 relation to the platen.

Referring to the drawings, the platen 10, of the usual type, preferably a wide platen, is rotatably mounted by means of an axle 11 in the end plates 12 and 13 of a platen-frame, and may be rotated by means of finger-wheels 14 and 15, respectively, or by line-space mechanism, including a ratchet-wheel 16, mounted on the axle 11.

The work-sheets 1 at the left-hand side of the platen are held against the platen by means of front feed-rolls 17 and rear feed-rolls 18, mounted on shafts 19 and 20, respectively; the shafts being carried by levers 21, 22, which are pressed upwardly by 15 springs (not shown), secured to a shaft 23, on which the levers 21 and 22 are pivoted. To release the feed-rolls 17 and 18, a release-shaft 24 is provided, which is cut away, on opposite sides thereof, to form depressions 25, having flat bottoms against which the lower ends of the levers 21, 22 20 rest when the parts are in normal position, as shown in Figure 2. The shaft 23 is supported in the end plates 12 and 13 of the platen-frame, and the feed-roll release-shaft 24 is rotatably supported in brackets 26, depending from the shaft 23. For rotating the release-shaft to cam out the levers 21 and 22 in such manner as to release the feed-rolls 17 and 18, there is fast to the release-shaft an arm 27 connected by a link 28 to an arm 29 fast on a shaft 30, which shaft 30 also has fast thereto an arm 31 carrying a finger-piece 32. This is the feed-roll release-40 mechanism common to Underwood type-writing machines. Depression of the finger-piece 32 causes the release-shaft 24 to be rotated in such manner as to release the feed-rolls; and, upon release of the finger-piece 32, the springs which act upon the levers 21 and 22 cause the feed-rolls to return to effective 45 position, and the operating connections to resume their normal positions.

It will be noted that no feed-rolls, such as 50 17 and 18, are shown at the right-hand side of the platen. This is because the work-sheets 2 at this side of the platen do not receive their line-feed movement by rotation of the platen. On the contrary, the work-sheets 2 receive their line-feed movement 55 while the platen is stationary, and, although held snugly to the platen for the printing operation, are movable freely over the surface of the platen by other mechanism, constituting a work-sheet-feeding attachment, 60 now to be described.

The paper-shelf 33 is shown in Figure 2 for guiding the work-sheets 2 down and around the platen, from front to rear. At 65 the front, the leading edges of the sheets 2

pass between and are held by opposing rolls 34 and 35. A table 36 is also provided at the front, which, as will presently appear, has the functions of serving as a guide for the work-sheets and as a support for the 70 work-sheets where erasures are to be effected. The rolls 34 have bearing on a shaft 37, each end of which is supported in an arm 38. The arms 38 are fast to a rock-shaft 39, the right-hand end of the shaft 39 having bearing in a triangular plate or bracket 40, secured by screws 41 to the right-hand end plate 13 of the platen-frame. The left-hand end of the shaft has bearing in a plate or bracket 42. The plate 42 is secured to the 80 usual paper-finger-rod 43, which, in turn, is supported at either end in the end plates of the platen-frame. The plate 42 is also supported in part by the platen 10, having rollers 44 which ride on the platen forward of the rod 43. The rolls 35, to which the rolls 34 are opposed, are carried by a shaft 45, the right and left hand ends of which have bearing in the plates 40 and 42, respectively. The end plates or brackets 40 and 42 90 and the feed-roll-carrying shaft 45 in this instance thus comprise the frame or body of the work-sheet-feeding attachment. The rollers 44 rest upon the platen about midway thereof and demark a line of division of the 95 platen for feeding two separate exposed work-sheets side by side.

Springs 46, which encircle the rock-shaft 39 to which the arms 38 are attached, bear at one end on a shaft 47 and at the other end grasp the roll-carrying shaft 37, tending to rock the arms 38 with the shaft 37 in such direction as to hold the rolls 34 against the rolls 35; thus to cause the work-sheet 2 to be gripped between the opposing rolls. 100 To release the work-sheet 2 from this grip, for purposes of insertion and removal of the sheet, the rolls 34 are releasable from the rolls 35, and, for this purpose, the shaft 47 has grooves or cross-cuts 49 therein, through which, as shown in Figure 2, the arms 38 pass when the rolls 34 are in effective position. The shaft 47 is, however, revoluble, so that, as shown in Figure 3, rotation thereof 105 will cause the arms 38 to be cammed up out of the grooves 49 and onto the circular periphery of the shaft 47, thereby rocking the arms 38 with the rolls 34 away from the rolls 35. The shaft 47 has its bearings in the plates 40 and 42. At its right-hand end, the shaft 47 is extended beyond the plate 40 and has fast thereto an arm 50, carrying a finger-piece 51, by means of which the shaft 47 110 may be turned to release and apply the rolls 34.

The rolls 34 not only hold the work-sheets at the right-hand side of the platen in position while the platen is rotated with the work-sheets at the left-hand side thereof, but also serve as a means for effecting a 115

line-space feed of the work-sheets at the right-hand side of the platen at such times as a feed of the right-hand sheets may be desired. For effecting feed of the right-hand work-sheets by means of the rollers 34 and 35, the shaft 45, which carries the rolls 35, is extended beyond the end plate 40 and has secured thereto a thumb-wheel 52, similar to the wheel 14 on the platen-shaft. The table 36 has openings 53 therein, through which the rolls 34 may engage the rolls 35.

This table has right-angle pieces or brackets 54 secured to the rear face thereof by rivets 55. Perpendicular wings 56 of these brackets have two hooks or yokes 57 and 58, respectively, formed therein. The shaft 39 serves as a hanger for the hooks or yokes 57, and the shaft 45 serves as a hanger for the hooks or yokes 58. The table 36 is, therefore, detachably and rigidly supported. The portion of the table 36 below the rolls 34 and 35 may serve as a guide for the work-sheets to the rolls, but, more particularly, is useful as a support against which erasures on the work-sheets may be effected.

In the usual typewriting machine, to effect an erasure, the platen is given a slight rotary movement to bring the printing to an accessible position above the printing instrumentalities, and the erasure is made directly against the platen. In the present machine, however, rotation of the platen is not ordinarily desired when printing is being effected on the work-sheets 2. Consequently, the movement of the sheet to a position where an erasure may be made is effected by turning the thumb-wheel 52 until the printing is brought opposite the lower part of the table 36. Above and to the rear of the rolls 34 and 35, the table 36 serves as a guide for the work-sheets, to prevent the same from fouling the shafts 39 and 47.

Variations may be resorted to within the scope of the invention, and portions of the improvements may be used without others.

Having thus described my invention, I claim:

1. In a typewriting machine for typing alternatively upon either of two work-sheets arranged side by side, in combination, a revolute platen, means co-acting with the platen at one side of the latter to cause work-sheets on the platen to be held thereto and to have line-space movement therewith, and means at the other side of the platen for holding work-sheets in fixed position for printing thereon against the platen, and for effecting a line-space movement of such work-sheets over the platen, independently of movement of the platen, said last-mentioned means being supported in part upon the platen about midway of the platen.

2. In a typewriting machine, in combina-

tion, a revolute platen, means co-acting with the platen at one side of the latter to cause work-sheets on the platen to be held thereto and to have line-space movement therewith, and sheet-gripping rolls free of the platen but partly supported thereon at the other side of the platen for effecting a line-space movement over the platen of work-sheets arranged beside the first-mentioned work-sheets independently of movement of the platen.

3. In a typewriting machine, in combination, a revolute platen, means co-acting with the platen at one side of the latter to cause work-sheets on the platen to be held thereto and to have line-space movement therewith, sheet-gripping rolls free of the platen but partly supported thereon at the other side of the platen for effecting a line-space movement over the platen of work-sheets arranged beside the first-mentioned work-sheets, and means for turning said rolls independently of the platen to move the second-mentioned work-sheets with respect to the platen.

4. In a typewriting machine for typing alternatively upon work-sheets arranged side by side and for advancing the sheets individually, a rotary platen, means at the left side of the platen for feeding the work-sheet at the left side, and wholly independent means at the right side of the platen extending about midway thereof and resting in part upon the platen for feeding the work-sheet at the right side, the construction and arrangement being such that either of the work-feeding means may be operated at will to advance the work-sheet controlled by it and that the other work-feeding means may remain effective but idle at the same time to hold stationary the work-sheet controlled by it.

5. In a typewriting machine for typing alternatively upon work-sheets arranged side by side and for line-feeding the sheets individually as they are typed, a rotary platen, means at the left side of the platen for feeding the work-sheet at the left side, and means at the right side of the platen for feeding the work-sheet at the right side, one of said means being operable at the will of the operator to advance the work-sheet controlled by it while the other work-feeding means remains effective but idle to hold stationary the work-sheet controlled by it, both of said means extending about midway of the platen and one of said means being supported in part upon the platen.

6. In a typewriting machine for typing alternatively upon work-sheet arranged side by side and for line-feeding the sheets individually as they are typed, a rotary platen, feed-rolls co-operating with the platen at one end thereof to control and feed the work-sheet at that end of the platen, co-

operating clamping rolls free of the platen and supported in part upon the platen at the other end thereof to hold stationary the work-sheet at that end of the platen during rotation of the platen to advance the first-mentioned work-sheet, and means to rotate the clamping rolls to advance the second-mentioned work-sheet while the first-mentioned work-sheet is held stationary by the platen and the co-operating feed-rolls.

7. In a typewriting machine for typing alternatively upon work-sheets arranged side by side, a revolute platen, work-feeding means at the right end of the platen for line-feeding the work-sheet at that end, work-feeding means at the left end of the platen for line-feeding a work-sheet at that end, said work-feeding means being wholly independent of each other and being non-conflicting so that either may remain effective but idle during operation of the other, and means for separately casting off the work-feeding means to render either of them ineffective while the other remains effective, or to render both of them ineffective at the same time, one of said work-feeding means being supported in part upon the platen.

8. In a typewriting machine, a platen, co-operating front and rear feed-rolls at the delivery side of the platen for feeding a work-sheet around the platen and relatively thereto, a shaft supporting the front feed-rolls, a shaft supporting the rear feed-rolls, said shafts being arranged one above the other, and a front paper-table having downwardly opening hooks engageable with the shafts for hanging the paper-table on the shafts in position to project between the feed-rolls, the paper-table being apertured between the feed-rolls to permit the feed-rolls to co-act through the table.

9. An attachment for typewriting machines comprising end brackets, a plurality of shafts connecting said brackets, front and rear feed-rolls supported by said shafts, and a front paper-table removably mounted on said shafts, said paper-table being arranged, when mounted on the shafts, to extend between the feed-rolls and being apertured to permit the co-action of the feed-rolls through the table.

10. An attachment for a unitary platen typewriting machine arranged to extend part-way across the platen of the machine to adapt the machine to feed two work-sheets side by side independently of each other, which comprises a pair of brackets, means for securing one of said brackets to the platen-frame of the machine, means to support the other bracket upon the surface of the platen, connections between the brackets, and co-operating feed-rolls carried by the attachment for feeding the work.

11. In a typewriting machine, a platen, a

paper-shelf at the introductory side of the platen for guiding work-sheets thereto, feed-rolls at one end of the platen to co-operate therewith in feeding a work-sheet, and an auxiliary feed-roll mechanism above the platen at its opposite end for feeding a second work-sheet beside the first, each sheet-feeding means being arranged to remain effective but idle during the operation of the other to hold its sheet stationary while the other sheet is being advanced, said auxiliary feed-roll mechanism being located above the platen and entirely between the plane of the paper-shelf and the writing plane, so as not to obstruct the insertion or feeding around the platen of a wide sheet substantially co-extensive with the platen.

12. In a typewriting machine, in combination, a revolute platen, a platen carriage, sheet-gripping rolls supported free of the platen, means co-operating with the rolls to cause work-sheets to lie against the platen at the printing line, means for turning the rolls independently of the platen to move the work-sheets over and with respect to the platen, a frame on which the rolls have bearing, and means for securing said frame to the platen carriage, said frame being in part supported on the platen.

13. In a typewriting machine, in combination, a revolute platen, a platen carriage, sheet-gripping rolls supported free of the platen, means co-operating with the rolls to cause work-sheets to lie against the platen at the printing line, means for turning the rolls independently of the platen to move the work-sheets over and with respect to the platen, a frame on which the rolls have bearing, and means for securing said frame to the platen carriage, said frame having rollers which ride upon and in part support the frame on the platen.

14. In a typewriting machine, in combination, a revolute platen, a sheet-gripping device free of the platen, means co-operating with the gripping device to cause work-sheets to lie against the platen at the printing line, means for feeding the work-sheets, as held by the gripping device, while the platen remains stationary, and a shelf between the platen and the gripping device against which erasures may be made upon movement of the sheets by the gripping device.

15. In a typewriting machine, in combination, a revolute platen, sheet-gripping rolls supported free of the platen, means co-operating with the rolls to cause work-sheets to lie against the platen at the printing line, means for turning the rolls independently of the platen to move the work-sheets over and with respect to the platen, and a plate through which the rolls engage each other and which serves as a combined erasing table and sheet guide.

16. In a typewriting machine, in combination, a revolute platen, a platen-frame, and a work-sheet-feeding attachment for feeding sheets independently of the platen, 5 said attachment comprising a frame extending from one end of the platen-frame part way across the platen and having its other end resting on the platen. 70
17. In a typewriting machine, in combination, a revolute platen, a platen-frame, and a work-sheet-feeding attachment for feeding sheets independently of the platen, 10 said attachment comprising a frame extending across the platen, having one end secured to the platen-frame and the other end resting on the platen about midway of the platen. 15
18. In a typewriting machine, in combination, a revolute platen, a platen-frame, 20 and a work-sheet-feeding attachment for feeding sheets independently of the platen, said attachment comprising a frame extending from one end of the platen-frame to a point about midway of the platen, said 25 attachment-frame including opposite end brackets, one of said end brackets being secured to said platen-frame and the other end bracket being supported upon the surface of the platen. 30
19. In a typewriting machine, in combination, a revolute platen, a platen-frame, and a work-sheet-feeding attachment for feeding sheets independently of the platen, 35 said attachment comprising a frame extending from one end of the platen-frame to a point about midway of the platen, said attachment-frame including opposite end brackets, one of said end brackets being secured to said platen-frame and the other 40 end bracket being supported upon the surface of the platen, said platen-supported end bracket having rollers for traversing the surface of the platen. 45
20. In a typewriting machine, in combination, a revolute platen, a platen-frame, and a work-sheet-feeding attachment to enable the machine to feed two exposed work-sheets side by side independently of each other, said attachment comprising a frame 50 extending from one end of the platen-frame part way across the platen and having its other end resting on the platen, means co-operative with the platen for feeding one of said work-sheets, and means on said attachment for feeding the other of said work-sheets independently of the platen. 55
21. In a typewriting machine, in combination, a revolute platen, a platen-frame, and a work-sheet-feeding attachment to enable the machine to feed two exposed work-sheets side by side independently of each other, said attachment comprising a frame 60 extending across the platen, having one end secured to the platen-frame and the other end resting on the platen about midway of the platen, means co-operative with the platen for feeding one of said work-sheets, and means on said attachment for feeding the other of said work-sheets independently of the platen. 65
22. In a typewriting machine, in combination, a revolute platen, a platen-frame, and a work-sheet-feeding attachment to enable the machine to feed two exposed work-sheets side by side independently of each other, said attachment comprising a frame 75 extending from one end of the platen-frame to a point about midway of the platen, said attachment-frame including opposite end brackets, one of said end brackets being secured to said platen-frame and the other end bracket being supported upon the surface of the platen, means co-operative with the platen for feeding one of said work-sheets and means on said attachment for feeding the other of said work-sheets independently of the platen. 80
23. In a typewriting machine, in combination, a revolute platen, a platen-frame, 85 and a work-sheet-feeding attachment to enable the machine to feed two exposed work-sheets side by side independently of each other, said attachment comprising a frame extending from one end of the platen-frame part way across the platen and having its other end resting on the platen, means co-operative with the platen for feeding one of said work-sheets, sheet-gripping feed-rolls on said attachment and means for turning said feed-rolls to effect line-spacing movement 90 of said last-mentioned work-sheet independently of the platen. 95
24. In a typewriting machine, in combination, a revolute platen, a platen-frame, and a work-sheet-feeding attachment to enable the machine to feed two exposed work-sheets side by side independently of each other, said attachment comprising a frame 100 extending across the platen, having one end secured to the platen-frame and the other end resting on the platen about midway of the platen, means co-operative with the platen for feeding one of said work-sheets, sheet-gripping feed-rolls on said attachment and means for turning said feed-rolls to effect line-spacing movement of said last-mentioned work-sheet independently of the platen. 105
25. In a typewriting machine, in combination, a revolute platen, a platen-frame, and a work-sheet-feeding attachment to enable the machine to feed two exposed work-sheets side by side independently of each other, said attachment comprising a frame 110 extending from one end of the platen-frame to a point about midway of the platen, said attachment-frame including opposite end brackets, one of said end brackets being secured to said platen-frame and the other end bracket being supported upon the sur- 115
- 120
- 125
- 130

face of the platen, means co-operative with the platen for feeding one of said work-sheets, sheet-gripping feed-rolls on said attachment and means for turning said feed-
5 rolls to effect line-spacing movement of said last-mentioned work-sheet independently of the platen.

26. In a typewriting machine, in combination, a revoluble platen, a platen-frame, 10 and a work-sheet-feeding attachment for feeding sheets independently of the platen, said attachment comprising a frame extending from one end of the platen-frame part way across the platen and having its 15 other end resting on the platen, coactive feeding rolls on said attachment and means for rendering said feeding rolls inoperative.
27. In a typewriting machine, in combination, a revoluble platen, a platen-frame, 20 and a work-sheet-feeding attachment for feeding sheets independently of the platen, said attachment comprising a frame extending from one end of the platen-frame part way across the platen and having its 25 other end resting on the platen, coactive feeding rolls on said attachment and means for rendering said feeding rolls inoperative, said means comprising a cam-shaft

mounted in said attachment-frame and a finger-piece for turning said cam-shaft. 30

28. In a typewriting machine, in combination, a revoluble platen, a platen-frame, and a work-sheet-feeding attachment for feeding sheets independently of the platen, said attachment comprising a frame extending from one end of the platen-frame part way across the platen and having its other end resting on the platen, work-sheet-feeding means on said attachment and a removable front paper-table co-operative 40 with said work-sheet-feeding means.

29. In a typewriting machine, in combination, a revoluble platen, a platen-frame, and a work-sheet-feeding attachment having one end secured to the platen-frame and the other end resting on and having support upon the platen, work-sheet-feeding means on said attachment and a front paper-table projecting between the feeding means with provision for engaging relation between said feeding means and the work-sheet. 45
